Howard M. Cohn(57) **CLAIM**

The ornamental design for a storage box as shown and described.

DESCRIPTION

FIG. 1 is a perspective view of a storage box showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of portion of FIG. 1;

FIG. 10 is an enlarged view of portion of FIG. 2; and,
FIG. 11 is another perspective view of the unfolded storage box.

The dash-dash broken lines depict portions of the storage box that form no part of the claimed design. The dot-dash broken lines in the drawings indicate cutoff boundaries for the enlarged detailed portion views and form no part of the claimed design.
